US00D410086S

United States Patent

[19]

Hacker et al.

[11] Patent Number: Des. 410,086

[45] Date of Patent: ** May 18, 1999

[54] SHUNT SENSOR FOR BLOOD GAS MEASUREMENT

[75] Inventors: **Thomas G. Hacker**, Anaheim; **Ronald G. Holder**, Laguna Niguel, both of Calif.

[73] Assignee: **Minnesota Mining and Manufacturing Company**, St. Paul, Minn.

[**] Term: 14 Years

[21] Appl. No.: 29/084,339

[22] Filed: Feb. 26, 1998

Related U.S. Application Data

[63] Continuation-in-part of application No. 08/810,954, Feb. 27, 1997, abandoned.

[51] LOC (6) Cl. 24-01

CLAIM

The ornamental design for a shunt sensor for blood gas measurement, as shown and described.

DESCRIPTION

FIG. 1 is a first perspective view of a shunt sensor for blood gas measurement showing our new design;

FIG. 2 is a second perspective view thereof;

FIG. 3 is a first end view thereof;

FIG. 4 is a left side view thereof, the right side view being a mirror image thereof;

FIG. 5 is a second end view thereof;

FIG. 6 is a top view thereof;

FIG. 7 is a bottom view thereof; and,

FIG. 8 is a perspective view thereof, with the broken line showing of the caps and filter assemblies being for illustrative purposes only and forming no part of the claimed design.
